UNITED STATES PATENT OFFICE.

KENNETH HOWIE, OF PHILADELPHIA, PENNSYLVANIA, ASSIGNOR TO WILDMAN MANUFACTURING COMPANY, OF NORRISTOWN, PENNSYLVANIA, A CORPORATION OF PENNSYLVANIA.

NEEDLE-PRESSING MEANS FOR KNITTING MACHINES.

1,407,684.

Specification of Letters Patent. Patented Feb. 21, 1922.

Application filed July 23, 1919. Serial No. 312,649.

To all whom it may concern:

Be it known that I, KENNETH HOWIE, a citizen of the United States, and resident of Philadelphia, Pennsylvania, have invented 5 certain new and useful Improvements in Needle - Pressing Means for Knitting Machines, of which the following is a specification.

The invention concerns means for making 10 tuck stitches on a spring beard needle machine using individual pressers, and it comprises pressers of special formation which when the presser cam is set in a certain pre- 15 scribed position or positions will not be op- erative on the specially formed pressers and hence the needles with which these pressers are, associated will not have their beards pressed and will not cast off the old loop and therefore these needles will tuck.

20 The invention is shown in the accompanying drawing in which

Fig. 1 represents a needle, a presser of ordinary form, and the cam for operating the presser; this cam being in section along a 25 line to one side of the center or high part thereof.

Fig. 1^a is a view similar to Fig. 1 but the line upon which this section is taken passes through the center or high part of the cam 30 and therefore this view shows the cam of greater width than Fig. 1. The needle is retracted partway in this figure and its beard is being pressed.

Fig. 1^b is a view similar to Fig. 1 but with 35 the needle retracted and having cast its old loop. The line upon which the section through the cam is taken is at the low part thereof at the opposite end of the cam from that shown in Fig. 1, and hence the width of 40 the cam in the figure is the same as that shown in Fig. 1.

Fig. 1^c is a detail plan view of the cam in relation to a part of a row of pressers and needles.

45 Fig. 2 is a view similar to Fig. 1 but with a different form of presser. Here, like in Fig. 1, the section of the cam is taken through its low part.

Fig. 2^a is a sectional view through the 50 high part of the cam, the needle being partly retracted.

Fig. 2^b is a sectional view also taken

through the high part of the cam with the needle fully retracted and forming a tuck stitch.

55

Figs. 3, 3^a and 3^b are views similar to Figs. 2, 2^a and 2^b, but with a different form of presser from either Fig. 1 or Fig. 2.

In these drawings 1 indicates the needle carrier or cylinder, 2 springs beard needles 60 of ordinary form and which are independently operated by any suitable cams as in ordinary practice. 3 indicates the pressers, there being one of these for each needle whose function it is to press the needle 65 beard when moved by its cam 4 into proper position to cause this pressing action to take place. Figure 1 represents the needle advanced to take the yarn. Figure 1^a represents it partly retracted and with its beard 70 pressed and Figure 1^b represents the needle retracted, having cast off its old loop. For the pressing action the presser is moved by the high part of cam 4 inwardly towards 75 the needle as shown in Figure 1^a. The cam acts on the outer edge of the presser, and this edge of this particular presser is plain and affords a bearing for the cam to work against. In Figures 2 to 3^b, however, the 80 pressers are formed with cut away portions so that the cam will not act thereon to move the presser to its operative position so long as the cam is in line with the cut out part. In these Figures 2 to 2^b, the low part of the cam is shown in section in Fig. 2 and the high part 85 in Figs. 2^a, 2^b.

In Figure 2 the cut out part is at the extreme upper outer corner of the presser leaving a space at 5, and when this form of presser comes opposite the high part of the 90 presser cam Figs. 2^a and 2^b it will be operated thereby and hence the corresponding needle will not be pressed and will hold its old loop for making tuck work. If, however, the presser cam is adjusted vertically to 95 lie in a horizontal plane below the plane of the notch or space 5, the presser will be operated by the cam and plain work will be produced on the corresponding needle. If, however, a presser or pressers like those 100 shown in Figures 3, 3^a and 3^b, be present in the same row with other pressers like those shown in Figures 1 and 2, the presser or pressers of Figure 3 will not be operated by the

lowered cam and the corresponding needles will do tuck work while the other needles controlled by the pressers of Figures 1 and 2 will be operated by the cam in this lowered position and the corresponding needles will do plain work. The presser of Figure 3, 3^a and 3^b, it will be noticed, is cut out in a plane below the plane of the cut out of the pressers shown in Figure 2, leaving an intact portion 6 above its notch¹⁵, so that when the presser cam is adjusted vertically to operate on this intact portion 6 these pressers will be effective in producing plain knitting together with the pressers and needles of Figures 1; 1^a, 1^b, but the pressers of Figures 2, 2^a, 2^b, will not be operated because the cut out at 5 will cause these pressers to miss the cam and tuck work on the needles of these pressers will be made.

20 As before pointed out, the cam in Fig. 3 is shown in section through its low part and in Figs. 3^a and 3^b it is shown in section through its high part.

All the pressers shown may be arranged 25 in the same needle row and pressers with other different locations of cut outs may be employed and grouped according to the pattern desired, so that by raising and lowering the cam 4 to different levels it will have a 30 selective action, operating certain of the pressers and missing others to give the prescribed design or pattern in plain and tuck work.

The invention can be used in various types 35 of machine such as hosiery machines or machines for making flat underwear.

The notches in the backs of the pressers are of a width measured vertically equal to the thickness of the presser cam so that this 40 cam need be moved only a small distance to change its operative relation to the presser.

I claim:

1. In combination in a spring beard needle knitting machine, a row of spring beard 45 needles, a series of upstanding pressers arranged in a row parallel with the row of needles, one of which pressers is arranged in front of each needle and having move-

ment at its upper part towards and from the needle for performing the pressing actions, and cam means, said cam means and row of pressers having relative traversing movement in a direction along the presser row and in said movement operating certain of the pressers and missing others, substantially as described. 55

2. In combination in a spring beard needle knitting machine a row of spring beard needles, a series of upstanding pressers, one arranged in front of each needle and having movement at their upper ends towards the needle beards for pressing and cam means operating against certain of said pressers and missing others, certain of said pressers having notches at their upper ends to miss 65 being pressed by the cam means, substantially as described.

3. In combination in a spring beard needle knitting machine, a row of spring beard needles, a series of upstanding pressers, one arranged in front of each needle and having movement at their upper ends to the spring beards for pressing, and cam means operating against certain of said pressers and missing others, said cam means being adjusted to 75 different horizontal planes to act at times on certain of the pressers and at other times on certain other pressers, substantially as described.

4. In combination in a knitting machine, a 80 row of spring beard needles, pressers arranged in a row parallel with the row of spring beard needles, one of said pressers being arranged opposite each needle and movable towards and from the same for 85 pressing, said pressers having different formations and cam means for operating the pressers, said cam means and row of pressers having relative traversing movement in a direction along the presser row and said 90 cam having movement to different horizontal planes for operating certain of said pressers at times and other pressers at other times.

In testimony whereof, I affix my signature.

KENNETH HOWIE.
